CLAIM

The ornamental design for a nasal aspirator, as shown and described.

DESCRIPTION

FIG. 1 is a perspective view of a nasal aspirator showing my new design.

FIG. 2 is a front view of a nasal aspirator.

FIG. 3 is a rear view of a nasal aspirator.

FIG. 4 is a left side view of a nasal aspirator.

FIG. 5 is a right side view of a nasal aspirator.

FIG. 6 is a top view of a nasal aspirator.

FIG. 7 is a bottom view of a nasal aspirator.

FIG. 8 is a rear side perspective view of a nasal aspirator; and,

FIG. 9 is an enlarged detail view of area 9 shown in FIG. 4. The broken lines in the drawings encircle portions of the claimed design that are illustrated in enlargements and form no part of the claimed design.
